(57) **CLAIM**

The ornamental design for an activity sensor, substantially as shown and described.

DESCRIPTION

FIG. 1 is a perspective view of an activity sensor in accordance with the present design.

FIG. 2 is a top view of the activity sensor in accordance with the present design.

FIG. 3 is a bottom view of the activity sensor in accordance with the present design.

FIG. 4 is a left side view of the activity sensor in accordance with the present design.

FIG. 5 is a right side view of the activity sensor in accordance with the present design.

FIG. 6 is a front view of the activity sensor in accordance with the present design.

FIG. 7 is a back view of the activity sensor in accordance with the present design; and,

FIG. 8 is a reference view of the activity sensor shown disposed within an article of footwear, such as a shoe.

The features shown in broken lines in the various Figures are for illustrating reference or environmental structure and form no part of the claimed design.
